UNITED STATES PATENT OFFICE

2,577,339

CEILING AND WALL PAINT APPLICATOR

Joseph O. Lee, West Allis, Wis.

Application February 24, 1949, Serial No. 78,146

2 Claims. (Cl. 91—62.5)

1

This invention relates to novel and useful improvements in applicators for use in applying a coating on a wall, ceiling or other surface.

An object of this invention is to apply paint or the like to a ceiling by an apparatus which lessens the possibility of having some of the paint applied inadvertently to an adjacent wall.

Another object of this invention is to apply paint to a wall without inadvertently applying some of the paint to the ceiling, the means for carrying out the above object including one or more frusto-conical rollers rotatively supported by a handle.

One of the main features of the present invention is the frusto-conical roller utilized in the capacity of a paint applicator, which roller is supported by a handle through the medium of a shaft and a receptacle, the shaft being disposed in non-parallel and non-perpendicular relationship with the longitudinal axis of the handle.

Ancillary objects and features of novelty will become apparent to those skilled in the art, in following the description of the preferred forms of the invention, illustrated in the accompanying drawings, wherein:

Figure 1 is an elevational view of the preferred form of the invention;

Figure 2 is a side view of the device shown in Figure 1, both Figures 1 and 2 showing schematically the invention in operation;

Figure 3 is a longitudinal sectional view of the device shown in Figure 2;

Figure 4 is a perspective detail of construction taken from a plane located by the section line 4—4 of Figure 3;

Figure 5 is an elevational view of another form of the invention, and;

Figure 6 is an end view of the embodiment shown in Figure 5.

Referring first to Figures 1—4 inclusive, the first form of the invention will be discussed in detail. The handle 10 is provided of any suitable material and of any desired length. This handle has a plate 12 at its upper end carried thereby accommodating screws 14. These screws pass through the bottom 16 of a receptacle generally indicated at 18, serve to fasten the handle to the receptacle. It is appreciated that if it is desired to replace the screws in the manufacture of the invention by rivets, spot welding or other types of structure, this may be resorted to.

The said receptacle 18 has a pair of end walls 20 and 22 which are inclined with respect to the longitudinal axis of the handle 10. The end walls are connected by suitable side walls to complete the said receptacle.

2

A pair of shafts 24 and 26 respectively are disposed at an angle with respect to the longitudinal axis of the handle 10 and the shaft 26 is carried in suitable brackets 28 and 30 respectively which extend from the ends 20 and 22 of the receptacle. The shaft 24 is carried by the subsequently described structures connected with the ends 20 and 22 of the receptacle. These shafts 24 and 26 are substantially parallel and are in non-perpendicular and non-parallel relationship with the longitudinal axis of the handle.

The shaft 26 is maintained in place on the bracket 30 by means of a pair of nuts 32 and 34 which are carried by one end of the shaft 15 and which are disposed on respective sides of the bracket 30. A spacing sleeve or thrust bearing 36 is disposed on the shaft 26 between one of the nuts 32 and a frusto-conical roller 38.

The shaft 24 has one end passed through the 20 side 20 of the receptacle and the other end is removably disposed in a substantially U-shaped bearing 40 carried by the said strap or bracket 30. The opposite end of the shaft 24 passes through the end 20 and a suitable guard or cage 25 42 may be carried on the external surface of the end 20 covering the last named end of the shaft 24 in order to prevent the escape of liquid 44 from the receptacle which is intended primarily to be paint.

The frusto-conical roller 38 has a pad 46 extending therearound and a second identical roller 48 is disposed on the shaft 24 also having a cover 50 extending therearound. The two rollers are in contact with each other and the lower roller is adapted to be partially submerged in the paint 35 44 or other liquid.

In operation of this form of the invention it is seen particularly from inspection of Figure 1 that due to the angularity of the sides 20 and 22 respectively and the disposition of the shafts 40 26 and 24 as well as the frusto-conical shape of the rollers, the corner of a ceiling may have paint applied thereto with substantially the remainder of the device spaced an appreciable amount from an adjacent wall. By this construction the inadvertent splashing or applying of paint to the adjacent wall is substantially obviated.

By the disposition of one of the rollers in the paint, it is seen that this embodiment of the invention is the self-feeding type structure. When 50 a wall is being painted by the use of the instant structure it is necessary only to tilt the handle 10 slightly so that the roller 38 engages the wall being painted and, the end walls either 20 or 22 55 of the receptacle will accordingly be spaced from the next adjacent wall.

Referring now to Figures 5 and 6 respectively a second form of the invention is illustrated. A handle 60 is supplied with a shank 62 which extends therefrom and has a substantially U-shaped end 64 fixed or integral therewith. A frusto-conical roller 66 has one leg of the U-shaped end portion 64 extending therethrough in order to serve the purpose of a journal. A suitable cover 68 is disposed on the roller 66 and the use of this form of the invention is substantially the same as the operation of the previously described form. This form is however of the manual feeding type that is, it is necessary for a painter to occasionally obtain a supply of paint on the cover 68 before applying the same on a wall or ceiling.

From the foregoing a clear understanding of the structure and operation of the invention is deemed apparent. It is also appreciated that certain variations may be made without departing from the spirit of the invention.

Having described the invention, what is claimed as new is:

1. A paint applicator comprising a handle having a receptacle attached thereto, said receptacle including side walls, a bottom wall and substantially parallel angularly inclined end walls, an upper and lower parallel shaft supported by said end walls and having an upper and a lower frusto-conical roller disposed respectively on said upper and lower shaft, said upper roller having its

upper edge spaced outwardly from the receptacle for contact with a ceiling and wall selectively, said upper roller having its wider end located directly above the narrower end of the lower roller and substantially parallel to the angularly inclined ends of the receptacle, the wider end of said upper roller having its upper edge spaced outwardly of the adjacent end of the receptacle so that the wider end of the upper roller and the adjacent end of the receptacle will be spaced from an adjacent wall when paint is being applied to one wall in a corner.

2. The combination of claim 1 and said handle having a longitudinal axis, and said angularly inclined end walls being parallel to each other and arranged with respect to the longitudinal axis of said handle so that planes passed through said end walls intersect the longitudinal axis of said handle.

JOSEPH O. LEE.
